Shoe Machinery Corporation, Flemington, N. J.,
a corporation of New Jersey

Application November 1, 1945, Serial No. 626,043

19 Claims. (Cl. 112—38)

1

The present invention relates primarily to improvements in hook needle sewing machines more particularly of the lockstitch type ordinarily employed for connecting the outsole with the welt of a Goodyear welt shoe, although in its broader aspects the invention is applicable to any type of sewing machine. An example of a machine to which the features of the present invention are applicable is disclosed in United States Letters Patent No. 2,056,670, granted October 6, 1936, upon an application of Joseph Gouldbourn et al.

In order to enable the work to be removed readily, machines of the type referred to above frequently are provided with power actuated cutters for severing the thread at the end of a seam. After severing the thread, the ends remaining in the machine may become displaced from proper position so that in starting a new seam effective sewing operations will not be performed. To avoid this result, it is customary to hold the ends of thread manually in their proper respective positions until the first few stitches of a new seam are completed. To insure proper insertion of the initial stitch in a new seam in certain machines employing a thread cutter, mechanical thread holders have been utilized to secure the thread ends in proper sewing position. In the use of mechanical thread holders to secure the thread ends, it is necessary to bring the thread into contact with the holders, usually before severing the thread, and, unless this is done, proper positioning of the thread ends will not be obtained.

One object of the present invention is to provide a sewing machine with means for securing the thread in the machine at a position to insure proper insertion of the initial stitch in a new seam when sewing operations are started, in such a way that no particular attention on the part of the machine operator will be required in applying the thread to the securing means, with the result that the entire operation of the machine will be simplified and rendered more effective. Other objects of the invention are to improve generally the construction of a sewing machine, particularly of the lockstitch type, in which a more reliable control than heretofore is obtained in thread manipulation and in uniformity with which stitches are set in the work.

In accordance with these objects, a machine embodying the features of the present invention comprises, in addition to the usual stitch forming devices, a thread cutter, a pneumatic thread holder means acting at the end of each seam in proximity to the thread cutter to secure the

2

thread remaining in the machine with certainty at a position which will insure proper insertion of the initial stitch of a new seam. This feature of the invention, as herein illustrated, includes 5 the provision of a valve for controlling the thread holder in attracting or releasing the thread at the desired times. The use of a pneumatic thread holder with a control valve is of particular advantage in a machine equipped with a thread cutter, in which the severed end of the thread remaining in the machine after the thread cutter has operated is attracted to the thread holder automatically by the flow of air induced thereby. When the machine is equipped with a thread 10 cutter, the thread holder valve of the invention 15 may be operated in suitable sequence with the operation of the thread cutter. In a particularly desirable embodiment of this feature, means are provided for retarding the operation of the control valve so that the thread will be retained 20 during insertion of the first few stitches of a seam.

In the present embodiment of the invention, the pneumatic thread holder consists of a suction 25 pump or its equivalent connected with an orifice on the presser foot or on the work support of the machine, or both, and the valve for controlling the thread holder is so arranged as to disconnect the suction side of the pump from the orifice and 30 at certain times to connect the orifice with the pressure side of the pump, thereby preventing accumulation of foreign material in the orifice when the holder is out of operation, as during sewing.

According to another feature of the invention, a frictional tensioning device is arranged to act 35 on the needle thread between the take-up and the looper to cause tension to be imparted to the thread while each loop is engaged with a loop taker and to be rendered inoperative during the 40 taking-up stroke of the take-up, thus positively preventing application of friction by said device. By so doing, the tension on the thread is increased 45 in such a way as to insure proper formation and setting of each stitch at the under surface of the work at which the take-up operates while the loop is being engaged by the loop taker. In a lockstitch sewing machine, such tensioning of the thread is effective in drawing the needle thread tightly against the work during each stitch formation. With the use of the tensioning device embodying this feature of the invention, preferably a second tensioning device also is employed 50 to assist the thread hook and looper in laying a loop of thread in the needle hook. When a second

tensioning device is employed in the form of the invention herein described, separate mechanisms are provided for actuating both tensioning devices in the proper timed relationship. As a convenient construction for operating the tensioning devices, connections are made with certain of the mechanisms already existing in the machine for operating the stitch forming devices and, as illustrated, one of the tensioning devices is connected with the thread hook actuating mechanism and the other with a thread lock actuating mechanism.

These and other features of the invention consist in certain devices, combinations and arrangements of parts hereinafter described and claimed, the advantages of which will be more clearly understood from a consideration of the following description taken in connection with the accompanying drawings, in which

Fig. 1 is a view in front elevation of a portion of the head of a sewing machine embodying the features of the present invention;

Fig. 2 is a sectional view on an enlarged scale, looking from the right-hand side of the machine, illustrating certain of the stitch forming devices in the machine, including the thread hook, thread measuring pull-off, and other devices;

Fig. 3 is a detail sectional side view on a further enlarged scale, illustrating mechanism for operating a frictional thread tensioning device for tightening the needle thread against the work;

Fig. 4 is a detail view of the same mechanism in front elevation;

Fig. 5 is a sectional view of a valve for controlling the pneumatic thread holder shown in a position for causing the thread to be secured;

Fig. 6 is a view of the same valve shown in a position to cause the thread to be released;

Fig. 7 is a detail view of the work support in the machine, illustrating a pneumatic thread holding orifice and conduit connected thereto;

Fig. 8 is a detail view partially in section of the work support and presser foot, illustrating the manner in which the thread ends are secured in position;

Fig. 9 is a perspective view of the presser foot with its thread securing orifice and suction conduits;

Fig. 10 is a detail view of certain of the stitch forming devices in the machine, illustrating their positions during the time at which thread is being given up to the loop taker; and

Fig. 11 is a similar view of the same parts taken during needle looping operations.

The illustrated machine is an outsole shoe sewing machine similar in construction, arrangement, and mode of operation to that of the patent to Gouldbourn et al., above identified, except as hereinafter described. The machine has a supporting column 12 at the upper end of which is a sewing head including stitch-forming devices and a driving and stopping mechanism actuated by a foot treadle (not shown) connected to a control rod 14 at the left side of the head as indicated in Fig. 1 of the drawings. When the control rod is raised, the machine is started and, when depressed by releasing the treadle, the machine is brought to rest in a manner more fully disclosed in the prior patent. Also the machine is equipped with a thread cutter similar to that disclosed in United States Letters Patent to Joseph Gouldbourn No. 1,985,605, granted December 25, 1934, except that in the machine of that patent mechanical means is employed to

hold the ends of thread remaining in the machine after the threads are severed.

The stitch-forming devices of the machine include a curved hook needle 16, a curved awl 18 (see Fig. 10), a needle looper 20, a thread hook or finger 22, a loop spreader 24, a loop taker or shuttle 26, a locking thread supply case 28, a rotary take-up 30 and a needle thread measuring pull-off 32 operating between a pair of thread locks 34 and 36 against which each stitch is set by the take-up. The work is clamped and fed in the illustrated machine by the action of a work support 38 and a presser foot 40, for a more complete explanation of the operation of which reference may be had to the Gouldbourn et al. patent.

In the machine of the present invention, the ends of thread remaining in the machine after being severed by the thread cutter are secured in place by a pneumatic thread holder, thus eliminating the use of mechanical thread holding parts with their actuating mechanisms within or surrounding the restricted spaces available about the sewing point. For securing the thread pneumatically, a pair of orifices 42, 44 (see Figs. 7, 8 and 9) are provided, one on the work engaging surface of the work support and the other on the presser foot, the orifices serving to terminate tubular conduits 46, 48 and 50 (best shown in Fig. 1 of the drawings), the conduits 46 and 48 serving as branches of the main conduit 50. The conduits extend between the orifices and a two-way valve 52 for controlling the flow of air in the orifices, and the valve 52 is connected to the suction side of an air pump 54 mounted at the underside of a frame 56 which supports the sewing head of the machine.

At the end of each sewing operation, the ends of both threads remaining in the machine are attracted by air flowing through the orifices and are secured separately in proper position to start a new seam against surfaces of the work support and presser foot through which the orifices open. The threads are readily attracted from the position in which they are severed to the mouths of the orifices by the air currents induced so that there is no necessity for presenting the threads accurately to the orifices by special manual movements of the work or threads in removing the work from the machine. For this purpose, the orifices of the thread holder are located in close proximity to the point of operation of the thread cutter.

The thread cutter comprises a single cutting blade (Fig. 1) 58 movably mounted on the machine for severing both threads above and against the surface of the work engaged by the presser foot. To permit both threads to be cut readily after the machine is brought to rest, the machine is brought to a stopping position with the needle loop of the final stitch pulled but part way down toward the work at the side of the presser foot so that a portion of the needle thread surrounding the shuttle thread extends above the work surface. Before severing the threads, sufficient lengths are withdrawn from the needle supply and locking thread case by pull-off devices similar to those described in the patent to Gouldbourn so that in forming the first stitch of a new seam there will be no danger of losing control of the severed ends remaining in the machine.

The means for operating the thread cutter consists of a rod 60 pivotally connected at its upper end to actuating mechanism for the thread cutter and at its lower end to a second foot treadle (also

not shown) separate from the treadle for controlling the driving and stopping mechanism in the machine. When the rod 60 is drawn downwardly, the cutter blade is actuated downwardly and inwardly of the machine against the upper surface of the work, which with the illustrated machine ordinarily comprises the projecting marginal portions of the welt and outsole of a shoe. In order for the thread cutter to act effectively, the machine is brought to rest at the end of a seam and the presser foot is lifted by the driving and stopping mechanism automatically from engagement with the work. As soon as the presser foot is lifted from the work, the thread cutter operating treadle may be depressed, causing the cutter knife to be projected against the threads and the threads to be severed in the manner previously indicated. After the thread cutter has been operated, the thread cutter treadle is released and the rod rises under the influence of a compression spring 62 coiled about the rod and arranged to act against an upper surface of the sewing head frame 56 and a collar 64 secured to the rod. Rising movement of the rod withdraws the thread cutter blade from engagement with the work, thus permitting the work to be withdrawn from the machine with the threads severed in close proximity to the work.

In operating the thread cutter in this way, mechanical connections between the thread cutter operating rod and the air controlled valve 52 cause the suction side of the pump 54 to be connected through the conduit to the orifices 42 and 44. The connections between the operating rod 60 and the valve include a pin 66 extending from the rod 60, a slotted arm of a bell crank lever 68 into the slot of which the pin 66 projects, a link 70 pivotally connected to the other arm of the bell crank lever 68 and terminating in a slotted end surrounding a pin 72 secured in a downwardly extending arm 74 fixed to a shaft forming a part of a movable cylindrical valve body 76, best shown in Figs. 5 and 6, the bell crank 68 being fulcrumed on a support 75 carried by the frame of the pump 54. The connections thus described are arranged to open the valve for connecting the conduit 50 to a suction pipe 78 extending from the pump 54 with the result that a flow of air is induced to flow into the orifices 42 and 44. Suction continues in the orifices so long as the machine remains at rest, the thread cutter operating rod connections being arranged to retain the valve in the position of Fig. 5 with the suction side of the pump connected to the conduit 50 for this purpose.

To retain the valve body 76 in thread securing position of Fig. 5 after being operated by the thread cutter rod 60 the lower end of the arm 74 fixed to the valve forms a detent for engagement with a latch arm on a lever 82. The lever 82 is mounted to turn on a stud 84 projecting from the supporting column 12 and is actuated yieldingly to swing its latch arm against the detent of the arm 74 by a tension spring 86 stretched between a pin on the lever and an eye screw 88 secured to the column 12. The extreme left end of the lever 82 is forked to receive a roll 90 so disposed as to be engaged by a finger projecting from a collar 92 clamped to the control rod 14 of the driving and stopping mechanism. When the control rod 14 is raised to start the machine in operation at the beginning of a seam, the finger on the collar 92 raises the roll 90 and swings the latch arm of the lever 82 away from the valve arm 74. As soon as this occurs, the valve body is turned from the position of Fig. 5 to the posi-

tion of Fig. 6 by contraction of a spring 94 connected at one end to a pin on the valve arm and at the other end to a second pin on the pump frame. During this movement, the pin 72 moves idly along the slot in the link 70.

In moving the valve body 76 to the position of Fig. 6, the suction pipe 78 is disconnected from the conduit 50 and connected to an inlet port 96 in the outside housing for the valve. The conduit 10 50 simultaneously is connected with a pressure tube 98 inserted in the exhaust side of the pump 54, the arrangement being such that, instead of inducing suction, a blast of compressed air is forced through the conduit and the orifices 42 and 15 44 to eject the threads and to eject any particle of leather or other foreign matter previously lodged therein from the orifices. In this way, the orifices are kept clear to insure free movement of air during the suction period. The blast of 20 air through the orifices continues throughout sewing operations and after the machine is brought to rest until the thread cutter is operated as just described.

In order to insure that in starting a new seam 25 the thread ends will be retained briefly in their respective positions in contact with the work support and presser foot so that the first few stitches will be inserted properly, the movement of the valve body from suction position of Fig. 5 to compression position of Fig. 6 is delayed until after 30 the machine starts. For this purpose, the valve arm 74 is pivotally connected at 100 with a piston rod 102, the piston of which operates within an air cylinder 104 pivoted at one end thereof to 35 the supporting column 12. The air cylinder 104 is provided with an adjustable bleeder valve 106 and a vent 108 to enable the time of movement of the valve to be regulated and to permit the valve to be rotated quickly after the desired period of 40 delay is completed. As soon as the piston of the rod 102 passes the vent 108, the valve is quickly shifted from the position of Fig. 5 to that of Fig. 6 by the spring 94. In the position of Fig. 5 in 45 which the suction pipe 78 is connected to the conduit 50 and the orifices in the work support and presser foot, the pressure tube 98 from the pump is vented to the open air through the valve and an outlet port 110 in the housing valve (see Figs. 5 and 6).

Besides ejecting foreign matter from the orifices, the force of the compressed air therethrough aids in keeping the work and the machine clear of such matter and definitely assists in improving the operation of the machine. Furthermore, the orifice 44 in the presser foot is directed across the path of the needle so that it tends to keep the needle loop free from small particles of leather or lint and assists in maintaining a reliable control of the loop under varying operational conditions, particularly while each needle loop is being disengaged from the loop taker and drawn toward the work.

To enable the work support and presser foot to move freely while clamping and releasing the 65 work and while feeding the work, the branch conduits 46 and 48 comprise flexible tubes between the work support and presser foot and the main conduit 50 which is of rigid construction. For connecting the branch tubes with their respective orifices 42 and 44 on the work support and presser foot, the work support and presser foot are drilled at 112 and provided with nipples 113 (see Figs. 7 and 9) between the drillings and the respective branch tubes.

The take-up 30 of the illustrated machine is of

the continuously rotating type which acts while each loop of thread drawn through the work by the needle is being carried about the loop taker to provide slack in the thread by giving up more thread than is required for the operation. The mechanism for actuating the take-up is contained partly within a hollow arm 114 of a gear casing, one member of which is connected to a sleeve 115 for rotating the take-up.

To insure that the thread between the needle looper and the work will have moderate tension applied thereto while the needle is being looped in each sewing cycle in spite of the slack provided, so that improper looping operations will not occur, the machine of the said Gouldbourn et al. patent has an auxiliary thread tensioning device comprising a downwardly extending leaf spring 116, as shown in Fig. 2. The leaf spring 116 is secured to an arm 118 on the upper end of which the thread finger 22 is formed. As the arm 118 moves rearwardly to assist in laying the thread in the barb of the needle, the leaf spring acts yieldingly against the thread which passes over a hub of an arm 320 supporting the thread lock 36. This occurs while the thread finger and the looper are acting to lay the thread in the needle barb and continues until the needle looping operation is completed. After the looping operation is completed, the arm 118 is moved forwardly and the leaf spring disengages the thread, as indicated in Fig. 2. During continued movement of the take-up, the thread becomes slack, particularly while each needle loop is being carried over the loop taker.

In order to tighten with a reliable tension the thread extending along the surface of the work engaged by the work support between the stitch being formed and the previously formed stitch, according to a further feature of the present invention, a second needle thread tensioning device is provided acting on the thread between the take-up and the looper during the time in which each individual loop passes over the top of the shuttle at a position of its greatest extension. In order to reduce the strain on the thread thereafter to a minimum during the take-up stroke of the take-up, the said second thread tensioning device disengages the thread and is rendered inoperative directly after the needle loop is released from the shuttle.

The second needle thread tensioning device embodying this feature of the invention is illustrated in Figs. 2, 3 and 4 and comprises a fixed wear plate 120 having side flanges between which the needle thread passes, mounted on a bracket 122 secured to the machine frame. Cooperating with the wear plate 120 and acting between its side flanges is a frictioning member 124 in the form of a rearwardly curving and laterally offset arm rotatably mounted on a bushing 126 surrounding a screw 128. The screw 128 passes loosely through a mounting plate 130 adjustably clamped to a portion of the machine frame and is threaded into an upstanding plate-like portion 132 of the frame, the sleeve and screw providing a rotatable mounting for both the arm 118 of the thread finger as well as for the arm of the tensioning member 124. The arm of the tensioning member 124 is formed with an offset to cause it to extend across in front of the thread finger arm 118, as illustrated in Fig. 4.

The mechanism for actuating the thread tensioning arm 124 includes a spherically headed bolt 134 clamped in an opening in the arm, a spring link 136 having at its upper end a socket to receive

the spherical head of the bolt 134 and at its lower end a similar socket to receive the spherical head of the bolt 138, secured within a threaded opening in the arm of a right angle lever 140. The lever

140 rotates on an inclined stud screw 142 threaded into a bracket 144 carried by the machine frame and, between forked portions of a downwardly extending arm of the lever 140, there projects a pin 146 forming a pivotal connection between a link 148 and a plunger 150. The link 148 and plunger 150 include a part of the mechanism for actuating the thread lock 34 which, as in the machine of the said Gouldbourn et al. patent, consists of a sleeve 152 rotatably mounted in a boss portion of the machine frame with a thread engaging block forming the thread lock 34 located in closely spaced relationship to a similar thread engaging block 154 provided with a rounded rib portion fitting within an L-shaped bracket 156 also secured to the machine frame. The connection between the rod 150 and the sleeve 152 includes a compression spring 158 coiled about a reduced portion of the rod and compressed against shoulders within the sleeve and on the rod, a pin 160 passing through the sleeve and a slot in the rod to prevent their separation.

The mechanism for actuating the thread lock 34 is otherwise the same as in the Gouldbourn et al. patent. Pivotedly connected to the link 148 is a cam actuated lever 162 fulcrumed at 164 on the machine frame and provided at its lower end with a roll 166 engaging a cam 168 on a sewing shaft 170.

The arrangement is such that, during the operation of the machine, the thread lock 34 moves toward the block 154 to grip the thread therebetween and thereafter the rod 150 continues its movement to apply a greater pressure through the spring 158 in clamping the thread. Depending upon the adjustment of the parts for its timing, a similar action takes place in the connections for actuating the thread tensioning member 124, although the force applied to the spring link 136 is less than that applied through the spring 158 of the thread lock 34, the spring link causing only a tensioning action on the thread rather than a clamping action to grip the thread against movement as in the thread lock.

By this construction and arrangement, both the thread tensioning devices, including the leaf spring 116 and the tensioning member 124, impart a frictional effect on the thread at different times in each sewing cycle. The timing of the tensioning devices can be best understood with reference to Figs. 10 and 11 of the drawings. In Fig. 11, the take-up 30 is shown at the beginning of its giving-up stroke, and the thread tensioning spring 116 is shown acting on the thread to assist the thread finger and looper while laying the thread in the hook of the needle to maintain a constant light uniform tension in the thread. As soon as the looping operation is completed, the needle draws the loop thus formed through the work and the leaf spring 116 disengages the thread as indicated in Fig. 10. As the take-up nears the upper end of its giving-up stroke, illustrated in Fig. 10, the frictioning member 124 engages the thread and presses it against the wear plate 120 to cause the thread at the under surface of the work engaging the work support to be tightened snugly against the work while the loop of needle thread is being carried over the top of the shuttle 26. As soon as the shuttle has rotated sufficiently to enable the needle loop to be disengaged therefrom, the tensioning member 124 is actuated

to disengage the thread and to relieve entirely the frictional effect. The needle loop is then pulled down against the work together with the encircled locking thread to complete the stitch in the usual way, both tensioning devices being inoperative during this part of the take-up stroke.

By arranging the orifice 42 on the work-engaging surface of the work support, the severed end of the thread is secured against withdrawal by the pressure of the work against it when the work is initially clamped in starting a new seam. Such an arrangement enables the use of a frictional tensioning device acting on the thread between the take-up and the looper to assist the operation of the looper in laying the thread in the hook of the needle during the first stitch of a new seam. The frictional tension applied to the thread by the tensioning device, thus, is insufficient to pull the thread from the orifice 42 after the work is clamped.

The nature and scope of the invention having been indicated and a construction embodying several features of the invention having been specifically described, what is claimed is:

1. A sewing machine having a work support, and stitch forming devices including a needle and a thread cutter, in combination with means acting after the cutter has operated to secure the severed end of the thread remaining in the machine at a position to insure proper insertion of the initial stitch of a new seam when sewing operations are restarted, comprising a pneumatic thread holder located in proximity to the thread cutter to attract the end of thread after being severed.

2. A sewing machine having a work support, stitch forming devices including a needle, work clamping means, and a thread cutter, in combination with means acting after the thread cutter has operated to secure the severed end of thread remaining in the machine at a position to insure proper insertion of the initial stitch of a new seam when sewing operations are restarted, comprising a suction pump and a conduit connected with the pump having an orifice on the work clamping means.

3. A sewing machine having a work support, stitch forming devices including a needle, a thread cutter, and means for operating the thread cutter, in combination with a pneumatic thread holder for securing the thread in the machine, a valve for controlling the thread holder, and connections between the operating means for the thread cutter and the valve arranged to cause the holder to secure the severed end of the thread after the thread cutter has operated.

4. A sewing machine having a work support, stitch forming devices including a needle, a thread cutter and means for operating the thread cutter, driving and stopping mechanism for causing the stitch forming devices to be actuated, and a rod for controlling the driving and stopping mechanism, in combination with a pneumatic thread holder for securing the end remaining in the machine of the thread severed by the thread cutter, a valve for controlling the thread holder, and operating connections between the controlling rod and the valve arranged to cause the holder to release the thread when sewing operations are restarted.

5. A sewing machine having a work support, stitch forming devices including a needle, a thread cutter and means for operating the thread cutter, driving and stopping mechanism for causing the stitch forming devices to be actuated, and

a rod for controlling the driving and stopping mechanism, in combination with a pneumatic thread holder for securing the end remaining in the machine of the thread severed by the thread cutter, a valve for controlling the thread holder, connections between the thread cutter operating means and the valve arranged to cause the holder to secure the thread when the thread cutter is operated, and other connections between the controlling rod and the valve arranged to cause the holder to release the thread when the stitch forming devices are started.

6. A sewing machine having a work support, stitch forming devices including a needle, a thread cutter and means for operating the thread cutter, driving and stopping mechanism for causing the stitch forming devices to be actuated, and a rod for controlling the driving and stopping mechanism, in combination with a pneumatic thread holder for securing the end remaining in the machine of the thread severed by the thread cutter, a valve for controlling the thread holder, connections between the thread cutter operating means and the valve arranged to cause the holder to secure the thread when the thread cutter is operated, other connections between the controlling rod and the valve arranged to cause the holder to release the thread when the stitch forming devices are started, and means for retarding the operation of the valve when the controlling rod connections are moved to cause the thread to be retained by the holder during insertion of the first few stitches of a new seam.

7. A sewing machine having a work support, stitch forming devices including a needle, a thread cutter and means for operating the thread cutter, driving and stopping mechanism for causing the stitch forming devices to be actuated, and a rod for controlling the driving and stopping mechanism, in combination with a pneumatic thread holder for securing the end remaining in the machine of the thread severed by the thread cutter, a valve for controlling the thread holder, a latch for retaining the valve in the position to which it is actuated by the thread cutter operating means, yielding means for actuating the valve in a direction to cause the holder to release the thread, and a connection between the controlling rod and the latch to release the valve for movement by the yielding means when the stitch forming devices are started.

8. A sewing machine having a work support, stitch forming devices including a needle, a thread cutter and means for operating the thread cutter, driving and stopping mechanism for causing the stitch forming devices to be actuated, and a rod for controlling the driving and stopping mechanism, in combination with a pneumatic thread holder for securing the end remaining in the machine of the thread severed by the thread cutter, a valve for controlling the thread holder, a latch for retaining the valve in the position to which it is actuated by the thread cutter operating means, yielding means for actuating the valve in a direction to cause the holder to release the thread, a connection between the controlling rod and the latch to release the valve for movement by the yielding means when the stitch forming devices are started, and a dash pot for retarding movement of the valve after being released by the latch to cause the thread to be retained by the holder during insertion of the first few stitches of a new seam.

9. A sewing machine having a work support and a presser foot for clamping the work, stitch

forming devices including a needle and a thread cutter, in combination with means for securing the end remaining in the machine of the thread severed by the thread cutter at a position to insure proper insertion of the initial stitch in the new seam when sewing operations are restarted, comprising suction producing means and a conduit having an orifice in the presser foot, a portion of which conduit includes a flexible tube to enable movement of the presser foot to clamp and release the work.

10. A lockstitch sewing machine having a work support and a presser foot for clamping and feeding the work, stitch forming devices including a needle and a shuttle, and a thread cutter, in combination with means for securing the ends remaining in the machine of the threads severed by the thread cutter at a position to insure proper insertion of the initial stitch in a new seam when sewing operations are restarted, comprising suction producing means and conduits having orifices on the presser foot and work support, a portion of each of which conduits includes a flexible tube to enable free work feeding movement of the work support and presser foot.

11. A sewing machine having stitch forming devices including a needle and work clamping means, in combination with means for securing the thread remaining in the machine at the end of a seam in a position to insure proper insertion of the initial stitch of a new seam when sewing operations are restarted, comprising an air pump, a conduit connected with the pump having an orifice in the work clamping means, and a valve in said conduit for producing suction in the orifice to secure the end of thread after sewing operations are terminated and for producing pressure in said conduit to prevent accumulation of foreign matter in said orifice during sewing operations.

12. A sewing machine having stitch forming devices including a needle and work clamping means, in combination with means for securing the thread remaining in the machine at the end of a seam in a position to insure proper insertion of the initial stitch of a new seam when sewing operations are restarted, comprising an air pump, a conduit connected with the pump having an orifice in the work clamping means, a valve in said conduit for producing suction in the orifice to secure the end of thread after sewing operations are terminated and for producing pressure in said conduit to prevent accumulation of foreign matter in said orifice during sewing operations, and means for retarding the movement of the valve when sewing operations are started to cause the thread to be retained by the thread securing means during insertion of the first few stitches.

13. A sewing machine having a work support and a presser foot for clamping the work and having an orifice, two-thread lockstitch forming devices, and a thread cutter acting to sever both threads when the stitch forming devices are brought to rest, in combination with means for securing the ends remaining in the machine of the threads severed by the thread cutter at a position to insure proper insertion of the initial stitch of a new seam when sewing operations are restarted, comprising suction producing means and conduit means having orifices in the work support and presser foot.

14. A sewing machine having a hook needle, a loop taker, a looper and a thread hook for laying a loop of thread in the needle hook, a take-up, and mechanism for actuating the take-up to pro-

vide slack in the needle thread during the giving-up stroke of the take-up, in combination with a pair of tensioning devices both of which engage the thread between the take-up and the looper and are rendered inoperative during the taking-up stroke of the take-up and one of which applies tension to the thread while each loop of thread is being laid in the needle hook and the other of which applies tension while each needle loop is being engaged by the loop taker to insure proper tightening of the needle thread against the work.

15. A sewing machine having a hook needle, a loop taker, a looper and a thread hook for laying a loop of thread in the needle hook, a take-up, mechanism for actuating the take-up to provide slack in the needle thread during the giving-up stroke of the take-up, in combination with a pair of tensioning devices both of which engage the thread between the take-up and the looper and are rendered inoperative during the taking-up stroke of the take-up and one of which applies tension to the thread while each loop of thread is being laid in the needle hook and the other of which applies tension while each needle loop is being engaged by the loop taker to insure proper tightening of the needle thread against the work, and separate mechanisms for actuating the tensioning devices at said times during each sewing cycle.

30. 16. A sewing machine having a hook needle, a loop taker, a looper and a thread hook for laying a loop of thread in the needle hook, a take-up, mechanism for actuating the take-up to provide slack in the needle thread during the giving-up stroke of the take-up, in combination with a pair of tensioning devices both of which engage the thread between the take-up and the looper and are rendered inoperative during the taking-up stroke of the take-up and one of which applies tension to the thread while each loop of thread is being laid in the needle hook and the other of which applies tension while each needle loop is being engaged by the loop taker to insure proper tightening of the needle thread against the work, and separate mechanisms including a connection with the thread hook for actuating the tensioning devices.

35. 17. A sewing machine having a hook needle, a looper and a thread hook for laying a loop of thread in the needle hook, a loop taker, a take-up, mechanism for actuating the take-up to provide slack in the needle thread as each needle loop is acted upon by the loop taker, thread measuring means including a pull-off and a thread lock, and mechanism for actuating said measuring means, in combination with a pair of thread tensioning devices acting on the thread between the take-up and the looper, and separate mechanisms for actuating said tensioning devices during each sewing cycle to relieve the tension on the thread during the major part of the taking-up stroke, comprising a connection with the thread hook and a connection with the mechanism for actuating the thread lock.

40. 18. A sewing machine having a hook needle, a looper, and a thread hook for laying a loop of thread in the needle hook, mechanism for actuating the thread hook, a loop taker, a take-up, thread measuring means including a pull-off and a thread lock, and mechanisms for actuating said measuring means, in combination with a pair of thread tensioning devices acting on the thread between the take-up and the looper, a connection between the thread hook actuating mechanism

13

and one of the tensioning devices for causing said device to apply tension to the thread while each loop of thread is being laid in the needle hook and to relieve the tension at other times, and a connection between the thread lock actuating mechanism and the other tensioning device for causing said tensioning device to apply a tension to the thread while each needle loop is being engaged by the loop taker.

19. A sewing machine having a work support, 10
stitch forming devices including a hook needle, a
looper, and a take-up, work clamping means, a
frictional tensioning device acting on the thread
between the take-up and the looper to assist the
operation of the looper in laying the thread in
the hook of the needle, and a thread cutter, in
combination with means acting after the thread
cutter has operated to secure the severed end of
thread remaining in the machine at a position on

14

the work clamping means where it will be engaged
by the work when clamped in starting a new seam
to insure proper insertion of the initial stitch,
comprising a suction pump and a conduit con-
nected with the pump having an orifice on the
work engaging surface of the clamping means.
